(57) **CLAIM**

The ornamental design for an electronic cigarette, as shown
and described.

DESCRIPTION

FIG. 1 is a perspective view of an electronic cigarette;
FIG. 2 is a front view of the electronic cigarette;
FIG. 3 is a rear view of the electronic cigarette;
FIG. 4 is a left side view of the electronic cigarette;
FIG. 5 is a right side view of the electronic cigarette;
FIG. 6 is a top view of the electronic cigarette; and,
FIG. 7 is a bottom view of the electronic cigarette.
The evenly spaced broken lines in the drawings depict
portions of the electronic cigarette that form no part of the
claimed design; the dash-dot-dash line represents a boundary
of the claimed design.
